DESIGN FOR A LADY'S HAT

Samuel Lish, Woodmere, N. Y.

Application May 25, 1940, Serial No. 92,579

Term of patent 3½ years

To all whom it may concern:

Be it known that I, Samuel Lish, a citizen of the United States, residing at Woodmere, Long Island, in the county of Nassau and State of New York, have invented a new, original, and ornamental Design for a Lady's Hat, of which the following is a specification, reference being had to the accompanying drawing, forming part thereof.

Fig. 1 is a front elevational view of a lady's hat showing my new design.

Fig. 2 is a side elevational view of Fig. 1.

I claim:

The ornamental design for a lady's hat, as shown.

SAMUEL LISH.
